UNITED STATES PATENT OFFICE.

CLARENCE O. WHITE, OF MINNEAPOLIS, MINNESOTA.

GASOLENE-ENGINE.

SPECIFICATION forming part of Letters Patent No. 634,679, dated October 10, 1899.

Application filed March 17, 1898. Serial No. 674,163. (No model.)

To all whom it may concern:

Be it known that I, CLARENCE O. WHITE, of the city of Minneapolis, county of Hennepin, State of Minnesota, have invented certain new and useful Improvements in Gasolene-Engines, of which the following is a specification.

My invention relates to gasolene-engines, and particularly to engines of the "Otto" cycle type.

The objects of the invention are to improve the construction and operation of gas-engines, to lighten and to cheapen the same, and particularly to improve the means of ignition, and also the means for controlling the admission of vapor to the cylinder and the exhaust therefrom, and, further, to provide means for regulating or adjusting the compression of the vapor or gases in the cylinder.

The invention consists generally in a gasolene-engine comprising a cylinder, piston, crank-shaft, &c., said cylinder having inlet and exhaust ports, in combination with an inlet-valve, a governor driven from the crank-shaft, valve-controlling levers, and a tripping-dog operating in connection therewith and adapted to be withheld by said governor to permit or prevent the entrance of gases or vapor to the cylinder; and, further, the invention consists in various constructions and in combinations of parts, all as hereinafter described, and particularly pointed out in the claims.

The invention will be more readily understood by reference to the accompanying drawings, forming part of this specification, and in which—

Figure 1 is a side elevation of a gasolene-engine embodying my invention. Fig. 2 is a sectional view thereof on the line $y-y$ of Fig. 1. Fig. 3 is a detail of the side of the engine, showing the tripping-dog device in another position. Fig. 4 is a side and sectional view substantially on the line $z-z$ of Fig. 2. Fig. 5 is an enlarged detail view of the governor and tripping device. Fig. 6 is a detail taken from Fig. 5. Fig. 7 is a detail section on line $x-x$ of Fig. 5.

As shown in the drawings, 2 represents the base of the engine; 3, the cylinder; 4, the cylinder-head; 5, the connecting-rod; 6, the crank-shaft, and 7 the belt or fly wheel. The inlet

and exhaust ports 8 and 9 of the engine (see Fig. 5) are covered by the chests or boxes 10 and 11, respectively. The chest 10 is provided with the mixing tube or chamber 12, depending therefrom and containing the valve 13 at its upper end. A weighted resistance-valve may be provided in the lower end of the mixing-tube 12, and the vapor or oil duct 60 enters between the two valves, the oil being sucked or drawn from the vaporizer-reservoir 14, the detail construction of which is not important to this application and is fully shown and described in my pending application, Serial No. 669,912, filed February 11, 1898. On the stem 15 of the valve 13 is the collar or cross-arm 16 to be engaged by the short arm 17, projecting from the small shaft 18, that extends through the walls of the mixing tube or chamber 12. To the outer end of the shaft 18 is connected an arm 19, and this in turn is connected by the light rod 20 to the swinging arm 21 on the rock-shaft 22. This rock-shaft is allowed to move only when an explosion is required, and when the same retains its position (shown in Fig. 1) the inlet-valve 13 will be held upon its seat and the entrance of fresh vapor or gas to the cylinder will be prevented, so that the engine will make a stroke without an explosion, the piston being moved by the momentum of the fly-wheel gathered from prior explosions. To thus control the operation of the valve 13, and hence the number of explosions in the cylinder, I employ the free-rocking bell-crank 23, loosely journaled on the end of the rocking shaft 22 and constantly actuated through the mechanism of the speed-reducing gears 24 25 and the connecting-rod 26, extending from a crank-pin on the side of the larger gear-wheel 25. This gear-wheel is journaled on the stub-shaft extending from the side of the engine-base. The bell-crank has its other arm connected to the plunger 27 of the gasolene-pump 28, which pump is thus operated at every stroke of the piston to force small quantities of gasolene through the pipe 29 into the small overflow-reservoir 14, from which the surplus of gasolene returns to the main supply-pipe 30 through the overflow-pipe 31. Now the connection between the free-moving arm 23 and the real valve-actuating arm 21 is made by means of the pivoted dog 32, that

is pivoted on the small stub-shaft 33, projecting from the inner side of the arm 23. This dog is adapted to drop over the end of the arm 21 and, locking thereon, will draw the arm 21 forward with the arm 23, thereby throwing up the restraining-arm 17 belonging to the valve 13 and permitting said valve 13 to open and let a new charge of vapor into the cylinder. Upon the return stroke of the arm 23 the arm 21 is forced back to its original position by the engagement of flanges or ribs 34 and 35 upon said arms 21 and 23. (See detail Fig. 7.) The locking operation of the tripping-dog is controlled by means of a small 15 governor 36, driven by a belt 37, extending from the crank-shaft, or a pulley that rotates with the gear 25. This governor is provided with the stem 38, that extends below its bearing, and when the governor-balls are raised 20 by too rapid rotation this stem will be forced down into the path of a wing or lug 39, that is provided upon the sleeve of which the dog 32 forms an integral part, the dog and this lug comprising a bell-crank pivoted on the 25 stub-shaft that extends from the arm 23. As illustrated by dotted lines in Fig. 5, the depression of the governor-spindle into the path of the lug 39 causes an engagement between 30 said parts only during the final backward movement of the arm 23, and the dog is lifted and prevented from engaging with the end of the valve-working arm 21, with the result that the arm 23 will start back upon its forward stroke without carrying the arm 21 with it, 35 said arm remaining in the position shown in full lines in Figs. 1, 5, and 6, and thus closing the entrance or inlet valve. When the stem of the governor is lifted by the depression of the balls, the lug 39 will pass beneath 40 the end of the stem and the hook of the dog will drop over the end of the arm 21. The downward movement of the dog 32 is limited by the engagement of the dog with a shoulder or stop provided on the inner side of the 45 arm 23.

In connection with the rocking shaft 22 I provide means to hold open the exhaust-valve during the time that the inlet valve is closed, except at moments when explosions occur. 50 This device comprises a stop arm or dog 40, arranged at the end of the rocking shaft 22 and adapted to open the exhaust-valve and to stand in the path of the lower end of the lever 41, that is connected with the exhaust-valve 42, the arm 40 standing in such position when the arm 21 is left by the arm 23 in its forward stroke—that is, when the arm 21 remains in the position shown in Figs. 1 and 3. The result is that there is no compression of 55 gases in the cylinder to impede the free rotation of the fly-wheel and the movement of the piston. On the other hand, the moment that the arm 21 is engaged by the dog and moves forward then the rocking shaft is rotated to 60 carry the arm 40 out of the path of the lower end of the lever 41, and the exhaust-valve is automatically closed by the spring 45 upon

the valve stem or rod, so that none of the fresh gases are allowed to escape through the exhaust-port. 70

It will be evident from the foregoing that my engine possesses a number of advantages over those now upon the market. One advantage to be named is the absolute and accurate control of the supply of vapor for the cylinder and the cutting off of surplus explosions. Further, all of the working parts of the engine except the piston are exposed and can be gotten at readily. 75

Having thus described my invention, I claim as new and desire to secure by Letters Patent—

1. In an explosion-engine, the combination, of the cylinder, with the inlet-valve therefor, the valve-locking means locking said valve 85 to prevent the entrance of gas to the cylinder, a constantly-driven actuating mechanism operative upon the locking mechanism or means, and a governor controlling the operative connection between said actuating mechanism and the locking mechanism, substantially as described. 90

2. In an explosion-engine, the combination, with the cylinder and the piston, of an inlet-valve controlling the entrance of gas to said cylinder, a locking mechanism in connection with said valve, a constantly positively and uniformly driven dog or pawl adapted to engage and operate said locking mechanism alternately to liberate and lock said valve, and a governor adapted to engage said dog or pawl and prevent the engagement thereof with said locking mechanism, whereby the opening of said valve is prevented, substantially as described. 100

3. The combination, in an explosion-engine, of the cylinder provided with inlet and exhaust ports having independent valves, with a common locking mechanism adapted to prevent the opening of the inlet-valve and prevent the closing of the exhaust-valve, and a constantly and uniformly driven mechanism carrying a governor-controlled dog or pawl to engage and operate said locking mechanism alternately to liberate and lock said inlet and exhaust valves, substantially as described. 110

4. The combination, in an explosion-engine, of the cylinder having inlet and exhaust valves, with a mechanism normally locking 120 said valves in closed and open positions, respectively, a constantly and uniformly driven dog or pawl adapted to engage and operate said locking mechanism to free said valves, and a governor adapted to prevent the operative engagement of said dog upon said locking mechanism, substantially as described. 125

5. The combination, in an explosion-engine, of the cylinder having an inlet opening or port, with a valve in said inlet opening or port, the rocking arm and connections for locking said valve, the constantly-driven arm, the pivoted dog carried thereby and adapted to engage said rocking arm, and the driven governor 130

mechanism to engage said dog and withhold the same from said rocking arm to prevent the movement of the same with the constantly-driven lever or arm and hence prevent the 5 opening of said valve, substantially as described.

6. The combination, in an explosion-engine, of the cylinder, the piston, connecting-rod and crank-shaft, with the inlet-valve, the rocking 10 arm 21 connected with said valve, the driven arm 23, means for operating the same from said crank-shaft, the pivoted dog or catch carried by said arm 23 to engage said arm 21 and lock the same to the arm 23, and the governor 15 driven from said crank-shaft and having a stem, which, when depressed, prevents the engagement of said dog with said lever 21, substantially as described.

7. The combination, in an explosion-engine, 20 of the cylinder, the piston, the connecting-rod and the crank-shaft, with the mixing-chamber and the inlet-valve, the vaporizer, the pump connected to said vaporizer, the rocking arm or lever 23 driven from said shaft and 25 wherefrom said pump is actuated, the rocking arm 21 having a locking connection with said valve, the dog carried by said arm 23 to

engage said arm 21, and the governor driven from said crank-shaft and having a stem adapted to be engaged by said dog and preventing the engagement of the dog with said 30 arm 21, whereby said inlet-valve is held shut, as and for the purpose specified.

8. The combination, in an explosion-engine, of the engine-base, the cylinder, the piston, 35 the connecting-rod, and the crank-shaft, with the inlet and exhaust valves, the rocking shaft 22, the arms 21 and 40 upon said shaft and operatively connected with said inlet and exhaust valves, respectively, the constantly- 40 driven rocking arm or lever 23, carrying a pawl or dog normally engaged with said arm 21, and the constantly-driven governor adapted to prevent the engagement of said dog with said arm 21 and to disengage the dog from 45 said arm, as and for the purpose specified.

In testimony whereof I have hereunto set my hand, this 8th day of March, 1898, at Minneapolis, Minnesota.

CLARENCE O. WHITE.
